HANDLING SILICON STEEL STRIP

August W. Ryan, Zanesville, Ohio, assignor to
The American Rolling Mill Company, Middle-
town, Ohio, a corporation of Ohio

Application April 27, 1939, Serial No. 276,401

8 Claims. (Cl. 80—2)

My invention relates to problems met with in the handling of thin metallic sheet and strip stock of relatively brittle character, and in particular thin silicon steel. There have recently been developed methods and machines for butt-welding thin silicon steel sheets so as to form endless lengths of wide strip material which can be coiled and shipped as such, or which can be slit and coiled into strip supplies for the substantially continuous operation of the punch presses making transformer laminations or other magnetic parts.

As showing a method and apparatus suitable for the formation of continuous thin strip by welding, I make reference to the copending application of Fay and Reed, Ser. No. 132,824 filed March 24, 1937 and entitled Welding process and apparatus for thin sheet metal, which has now matured into Patent No. 2,172,080, dated September 5, 1939. In the practice of that invention the silicon steel sheets are sheared at their ends while clamped adjacent the line of cut under a given pressure effective over a given area; and the sheet ends are butted for welding and clamped in butted relationship under the same pressures effective over the same areas, whereby an accurately butted relationship is secured in spite of the thinness of the material and its lack of flatness. During welding, precautions are maintained to prevent the heat from disturbing the butted relationship.

When a sheet has been welded to the trailing end of a preformed strip, the strip is moved forward until the line of weld is positioned at a rolling device where the weld is rolled. Then the material is coiled; but because of its lack of flatness, it has been found necessary in making a tight, even coil, to coil the material about a vertical mandrel with the coil resting on a flange on the mandrel, and at frequent intervals to restrain the strip material moving toward the mandrel during rotation of the mandrel so as to tighten the coil. The necessity of coiling vertically requires that the strip, after welding be twisted so as to bring it from the horizontal to the vertical position. This mode and apparatus for coiling is described in the copending application of Asbury and Reed, Serial No. 132,826, filed March 24, 1937 and entitled Process and apparatus for coiling strip metal.

In the commercial practice of these procedures, by reason of the extreme brittleness of the thin silicon steel, need has been experienced for a mode of rendering the silicon steel more ductile at various points in the apparatus assembly.

Particularly is this need apparent at two points: where the silicon steel is being rolled at the line of weld, and at the point where the silicon steel begins to be twisted from the horizontal to the vertical plane, though the principles of my invention may be applied at any point desired in the train of operations, as will be apparent hereinafter.

The primary object of my invention is to provide a simple, inexpensive and effective solution of the problem set forth above.

I have found that sufficient ductility can be developed in the strip by the application of moderate and controlled degrees of heat at the points where greater ductility is desired, and that a temporary ductility may be imparted to prevent breaking or tearing the sheet or strip, without impairing the carefully built-up magnetic characteristics of the product which are the result in part at least of previous heat treatments at higher temperature. In order to gain my results, however, the application of heat must be carefully controlled. If a high temperature flame is employed it must be kept moving with reference to the material if the material is stationary during application, or if the material is moving, precautions must be taken to prevent continued application of the flame if the material stops. Since by its nature the process of forming endless strips is discontinuous, and since the material is subject to step-by-step and sometimes quite erratic movements, it is advisable to provide automatic means for flame control, especially where it is necessary to develop ductility in the material at a plurality of points. The necessary temperature is in the neighborhood of 300° F. If this temperature is not approached satisfactory ductility will not be developed in the material. If this temperature is greatly exceeded there is grave danger of impairing the magnetic properties of the material.

The more specific objects of my invention will be apparent to one skilled in the art upon reading these specifications; and I accomplish them by that certain construction and arrangement of parts and in that procedure of which I shall now set forth a specific embodiment. Reference is made to the drawing wherein:

Figure 1 is a diagrammatic plan view showing an apparatus assembly to which my invention is applied.

Figure 2 is a similar view which is a vertical section of a portion of the apparatus of Figure 1 taken along the line 2—2 in that figure.

Figure 3 is a fragmentary elevational view of

the rolling apparatus taken along the line 3—3 of Figure 2.

Figure 4 is a view of a manifold burner, along the line 4—4 of Figure 2.

The drawing is diagrammatic in character.

In the drawing, 5 indicates a shear having a table 6 on which sheets are sheared. A welding apparatus is generally indicated at 7. It has a table 8 on which fresh sheets are positioned to be welded to the trailing end of a strip 9 previously formed by welding. The manner of the welding and the apparatus involved in this exemplary embodiment of the invention can be ascertained from the copending application first above referred to. They form no necessary limitation on the invention here involved.

The welded joins in the strip 9 are rolled by a rolling device indicated generally at 10. The strip is twisted beyond the rolling device so as to be brought to a vertical plane and to pass around a sheave 11. While being twisted, the strip is supported in various angular positions by suitable supporting means 13. The direction of movement of the strip is changed by the sheave 11, and it is brought through supporting means 12 to a coiling mandrel 14. The mandrel is driven by a motor 15, which also drives, through a transmission 16, a braking device 17 operated by a cam, which acts at frequent intervals to restrain the strip and tighten the coil on the mandrel.

The rolling device may have various forms. The type illustrated has, mounted on a suitable framework, an anvil 18 above which is a rail or bridge 19. A carriage 20 rides on the bridge so as to traverse the work. This carriage bears one or more rolls 21 by which the transverse welds in the work are rolled against the anvil. The carriage is fastened to an endless chain 22 which passes over sheaves 23 and 24 at each end of the bridge. The sheave 23 is fast to a shaft carrying a bevel gear 25 which meshes with bevel gears 26 and 27 rotatably mounted on a shaft 28. A motor 29, through a gear box 30, drives the shaft 28. A clutch member 31 is splined on the shaft, and serves to connect the shaft alternatively to the gears 26 and 27, whereby the carriage may be driven through the chain in either direction. The clutch member may be actuated by a clutch lever shown diagrammatically at 32, which is urged in one direction by a spring 33 and may be moved in another direction by a solenoid or magnet 34. This arrangement is diagrammatic, primarily, and I prefer to use a magnetic clutch.

The motor 29 is supplied with current from power mains 35. It may be started by a hand switch 36 in its circuit. As the carriage moves forward, a pin 37 thereon actuates a switch 38 in a holding circuit for the motor so as to close it. Thus the hand switch 36 may be released; but the motor will continue to run.

When the carriage has traversed the work and nears the opposite end of the bridge, the pin 37 actuates a switch 39 in the circuit of the solenoid 34 so as to open that circuit, allowing the clutch to shift to the reverse position. The carriage then starts its reverse travel. When it returns to starting position, the pin 37 opens switch 38, thereby stopping the motor. The pin also resets switch 39 through the rod arrangement 40. The solenoid 34 is not again energized until the motor is started, since the switches 36 and 38 are in its feed circuit also, as will be seen.

I mount upon the carriage a high pressure gas burner (41 in Figure 3) to heat the work as it is

being rolled. This burner is connected by a flexible tubing 42 to a gas supply line 43. A valve 44 is provided; and the valve is by-passed by a line 45 containing a pilot valve 46 which feeds enough gas to the burner at all times to maintain an ignition flame, but not enough to heat the work. I may couple the valve 44 to the clutch lever (or magnetic clutch), as by a chain 47, so that the valve is opened when the clutch is in the forward position. The burner 41, located ahead of the rolls 21 on the carriage in the direction of forward motion, thus is supplied with gas under full working pressure to heat the work during the forward movement of the carriage. When the carriage starts its return travel the working gas pressure is cut off, and it is not reapplied until the start of the next rolling operation.

It has been indicated that it is desirable to apply heat to the strip at the point where the twisting action begins. I locate at this point a manifold burner 48 extending across the strip. This burner is connected to the gas main 43 through a valve 49. This valve is again bypassed by a line 50 containing a pilot valve 51, permitting such a flow of gas at all times as will maintain the burner alight without heating the sheet to any great degree. This is an instance where the burner is stationary. Consequently it must be turned on to apply the treating heat to the strip only when the strip is moving. Not only, however, must it be turned off as soon as the strip stops, it must also be turned on automatically as soon as the strip starts to move.

A switch is arranged in the circuit of the motor 15, to be operated by the strip. The formation of the strip is necessarily a step-by-step operation, and the strip is stationary while being welded and rolled, and then is moved forward in such a way as to position the trailing end of the strip at the welding station for the joining of a fresh sheet, and so as to position the newly made weld at the rolling station. The forward movement of the strip is accomplished by motorized pinch rolls 52 under the control of the operator.

When the pinch rolls feed the strip forward, slackness may be formed in it as at 53. I arrange, as an exemplary structure a weight operated switch 54, which controls the motor 15 so as to set it in operation as soon as the aforesaid slackness forms. The valve 49 may be an electrical valve with a solenoid 55 in the circuit of the motor 15. Thus as soon as the motor is energized so that the strip 9 begins to move, the burner 48 is turned on to apply the full working heat to the strip.

When the pinch rolls 52 have fed the strip forward sufficiently to position its trailing end at the welding station they stop. The coiler motor 15 continues to operate, however, until the slackness 53 has been taken out of the strip. When this happens, the weight 56 is lifted by the strip, operating the switch 54 and de-energizing the motor. Also, the electrical valve 49 is de-energized and the gas is cut off from the burner 48, excepting that which passes through the pilot line 50.

Modifications may be made in my invention without departing from the spirit of it. Having thus described my invention, what I claim as new and desire to secure by Letters Patent is:

1. In apparatus of the character described, in combination with welding means for a strip, take up means for said strip, means controlling the operation of said take up means in accordance

with the formation of slackness in said strip, means to apply heat to said strip, and means whereby said controlling means is made to affect the production of heat by said last mentioned means.

2. In a device of the character described, means for moving silicon steel strip, means for operating upon said strip during its movement in a manner to change its configuration so as to require greater ductility in the strip than the strip may possess, and means for applying heat to the said strip to render it more ductile during the said operation thereon, the said heat applying means being located adjacent the said operating means so as to be capable of heating said strip while it is being operated upon, and means for controlling the operation of said heat applying means in accordance with the movement of said strip as produced by said moving means, whereby said heat applying means is caused to be effective in applying a working heat to said strip only during periods of movement of said strip.

3. In apparatus of the character described, cross rolling means for transverse seams in a strip, said means comprising a carriage, means for driving said carriage so as to cause it to traverse the strip, means for applying heat to said strip, mounted on said carriage, and means for rendering said heat applying means effective only during periods of motion of said carriage.

4. In apparatus of the character described, cross rolling means for transverse seams in a strip, said means comprising a carriage, means for driving said carriage so as to cause it to traverse the strip, means for applying heat to said strip, mounted on said carriage, and means for rendering said heat applying means effective only during periods of motion of said carriage, said last mentioned means comprising control means for said heat applying means, means for controlling the movements of said carriage, and an operative connection between said last mentioned means.

5. In apparatus of the character described, cross rolling means for transverse welds in a strip, comprising a carriage having forward and rearward movement across the strip, a motor for said carriage, magnetic means including a clutch for determining the forward and reverse movement of said carriage, a burner mounted on said

carriage, a fuel supply for said burner, having a valve, and a connection between said valve and said clutch means, whereby said burner is fed with fuel under full working pressure during the movement of said carriage in but one direction.

6. In apparatus of the character described, cross rolling means for transverse welds in a strip, comprising a carriage having forward and rearward movement across the strip, a motor for said carriage, magnetic means including a clutch for determining the forward and reverse movement of said carriage, a burner mounted on said carriage, a fuel supply for said burner, having a valve, and a connection between said valve and said clutch means, whereby said burner is fed with fuel under full working pressure during the movement of said carriage in but one direction, said motor having a circuit, and a connection between said circuit and said magnetic means such that when said motor is de-energized said valve is closed.

7. In apparatus of the character described, cross rolling means for transverse welds in a strip, comprising a carriage having forward and rearward movement across the strip, a motor for said carriage, magnetic means including a clutch for determining the forward and reverse movement of said carriage, a burner mounted on said carriage, a fuel supply for said burner, having a valve, and a connection between said valve and said clutch means, whereby said burner is fed with fuel under full working pressure during the movement of said carriage in but one direction, said motor having a circuit, and a connection between said circuit and said magnetic means such that when said motor is de-energized said valve is closed, and take up means for said strip including a motor, a circuit for said motor, a switch in said circuit operated by slackness in said strip, additional means for applying heat to said strip having a fuel supply with a valve, and magnetic means controlling said valve and located in said circuit so as to be affected by said switch.

8. Apparatus claimed in claim 2 wherein said means for applying heat is a burner, and said controlling means affects the quantity of fuel consumed by said burner.
